COMBINED COLLAPSIBLE TUBE HOLDER AND DISPENSER

Filed May 17, 1946

UNITED STATES PATENT OFFICE

2,507,651

COMBINED COLLAPSIBLE TUBE HOLDER
AND DISPENSER

Donald Small, Johnstown, Pa.

Application May 17, 1946, Serial No. 670,574

1 Claim. (Cl. 222—100)

1

The present invention relates to new and useful improvements in paste dispensing devices, and more particularly to a device of this character adapted for dispensing tooth paste, shaving cream, and similar paste products from a collapsible tube.

An important object of the present invention is to provide a container for a tube of paste adapted for attaching to a wall or other suitable supporting structure, the threaded neck of the tube being connected to a discharge spout at the lower end of the container and connecting the rear end of the tube to a slotted key for winding the tube thereon in a manner to extrude the paste from the spout onto a tooth brush or other type of brush in accordance with the character of the paste being dispensed.

A further object of the present invention is to provide a device of this character including a dispensing spout shaped to discharge the paste forwardly and in ribbon form onto the brush.

A still further object is to provide a container for the tube of paste and including a unitary front and top wall removably attached to the container to facilitate removal of the empty tube for replacing with a full tube.

Another object is to provide a device of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a front elevational view.

Figure 2 is a side elevational view with parts broken away and shown in section.

Figure 3 is a transverse sectional view taken substantially on a line 3—3 of Figure 1.

Figure 4 is a fragmentary sectional view through the spout taken substantially on a line 4—4 of Figure 1.

Referring now to the drawing in detail, where for the purpose of illustration I have disclosed a preferred embodiment of the invention, the numeral 5 designates an attaching plate adapted for attaching to the side of a wall or other suitable supporting structure, the attaching plate being secured in position in any conventional manner.

The attaching plate includes a forwardly projecting relatively wide vertical rib 6 having its up-

2

per end formed with a flange 7 projecting upwardly in spaced relation from the wall or other supporting structure, as indicated in Figure 2 of the drawing.

5 The lower end of the attaching plate is formed with a forwardly projecting shelf 8 having a threaded opening 9 therein for receiving the threaded neck 10 of a paste tube 11, the tube being supported in an upstanding position on the shelf.

The bottom of the shelf is formed with a forwardly inclined spout 12 including a passage 13 communicating with the opening 9, the passage terminating in a flat tapering discharge mouth 14 at the front lower portion of the spout. The lips of the mouth 14 are arranged in such a manner as to spread the paste in ribbon or other form when discharged from the mouth of the spout, and the spout 12 is constructed of material having sufficient resiliency as to be of a self-opening and self-closing type, thus preventing the paste from becoming exposed when not in use.

A cover designated generally at 15 is provided for the tube of paste 11, the cover including side walls 16, a front wall 17, and a top wall 18. The edges of the side walls 16 are placed outwardly at the sides of the rib 6 and the under side of the top wall 18 is formed with a transverse channel 19 adapted to receive the upwardly projecting flange 7 of the attaching plate, whereby to retain the cover in position over the tube of paste and secured to the attaching plate.

The rib 6 of the attaching plate is formed with a vertically extending groove 20 and the front wall 17 of the cover is formed with a vertically extending slot 21 through which a winding key 22 is inserted with its inner end adapted to travel in the groove 20. The key 22 is formed with a longitudinally extending slot 23 adapted to receive the upper end of the paste tube 11 for winding the tube thereon and to compress the contents of the tube to extrude the same from the spout 12. The key 22 is provided at its outer end with a knurled manipulating knob 24, and as the contents of the tube are discharged, the empty upper portion of the tube will be wound on the key 22 while the key travels downwardly in the groove 20 and the slot 21.

The side edges of the front wall 17 are formed with outwardly projecting flanges 25 and the side walls 16, adjacent their upper ends, are formed with spaced-apart lugs 26 adapted for engagement by the brush head 27 of a tooth brush to support the brush against the sides of the container with the handles 28 of the brush extended

downwardly along the sides 16 behind the flanges 25.

If desired, the key 24 may be operatively connected with a conventional type of coin controlled mechanism to control the dispensing of the paste.

It is believed the details of construction, manner of operation and advantages of the device will be readily understood from the foregoing without further detailed explanation.

While I have shown and described a preferred embodiment of the invention, it will be apparent that various changes in construction may be made without departing from the spirit of the invention as herein described, and the scope of the appended claim.

Having thus described the invention, what is claimed is:

A collapsible tube holder and dispenser comprising a substantially flat elongated mounting plate arranged substantially vertically and secured to a support, said mounting plate being provided upon its forward face with a wide substantially thin elongated flat rib which extends for substantially the entire length of the mounting plate, the rib being provided substantially at its transverse center with a narrow elongated substantially vertically extending groove extending for substantially the entire length of the rib and mounting plate, the mounting plate being provided at its top with a short upstanding flange which projects above the top of the mounting plate and is disposed forwardly of the rear face of the mounting plate, the mounting plate being provided at its bottom end with an integral forwardly projecting substantially horizontal shelf extension having a central vertical screw-threaded opening formed therein, said screw-threaded opening being spaced laterally forwardly of the rib of the mounting plate, the screw-threaded opening receiving the screw-threaded

neck of a collapsible tube disposed inverted and substantially vertically upon the substantially horizontal extension and extending upwardly therefrom and forwardly of and adjacent to the rib of the mounting plate, a cover detachably mounted upon the mounting plate and including a substantially flat forward side spaced from the mounting plate and provided with a central vertical slot disposed in lateral alignment with the groove of the rib, the slot extending for substantially the entire length of the cover and mounting plate, the cover including integral substantially vertical sides having their inner free edges engaging upon opposite sides of the rib, the cover including an integral flat top provided in its bottom face with a groove receiving the upstanding flange of the mounting plate therein, the inner side and bottom of the cover being open, and a winding key extending transversely through the slot of the cover and having its inner end engaging within the groove of the rib and connected with the free end of the collapsible tube between the mounting plate and forward side of the cover and operable for winding up the tube to dispense its contents.

DONALD SMALL.
